RING DISPLAY BOX

Samuel Tylon, Cleveland, Ohio

Application August 22, 1952, Serial No. 21,156

Term of patent 14 years

(Cl. D80—5)

To all whom it may concern:

Be it known that I, Samuel Tylon, a citizen of the United States of America, residing at Cleveland, in the county of Cuyahoga and State of Ohio, have invented a new, original, and ornamental Design for a Ring Display Box, of which the following is a specification, reference being had to the accompanying drawing, forming a part thereof.

In the drawing:

Figure 1 is a plan view of a ring display box, embodying my new design,

Figure 2 is a perspective view of the design in open position,

Figure 3 is a rear elevational view of the design,

Figure 4 is a front elevational view of the design,

Figure 5 is a side elevational view thereof, the other side being similarly ornamented.

I claim:

The ornamental design for a ring display box, as shown and described.

SAMUEL TYLON.
